UNITED STATES PATENT OFFICE

EUGENE F. IRWIN, OF MEDFORD, MASSACHUSETTS

DAILY PLAN BOOK

Application filed July 3, 1929. Serial No. 375,771.

This invention relates generally to certain new and useful improvements in daily plan books and is more particularly designed for the use of teachers in schools.

A primary object of my invention is to provide means for readily and visually indicating the subjects taught, the specific subject or subjects taught on certain days of the school week, and the particular branch of that specific subject being taught on that day.

A further object is to prevent the printing of each individual sheet.

A still further object is to provide means adapted to be used as a book mark.

Another object is to provide means for concealing confidential matter.

The foregoing and other objects and advantages of the invention will be in part pointed out and in part be obvious from the description thereof to follow taken in connection with the annexed drawings, in which—

Figure 1 is a view of the improved book in opened position with the flap in extended or opened position.

Figure 2 is a view similar to Figure 1 but showing the flap in folded or closed position.

Figure 3 is a perspective view showing the use of the flap as a book mark.

Figure 4 is an end view showing how the flap is folded.

Referring to the figures of the drawings in detail, the leaves 10 of the cover are hinged or folded at the center as is usual and are adapted to hold sheets 11 of paper therebetween in the ordinary manner. The cover is made of card board or other suitable material having a relatively stiff body. The pages 11 are the same size substantially as the cover so that no portion of the page extends beyond the marginal edges of the cover. These pages are ruled vertically so as to provide vertical spaces 12. I have shown eight of these spaces but it will be understood that as many as desired may be provided. Above the column to the left of the page I have left a blank but above each of the other columns I have printed on the inside cover of the book the day of the week, thus I have shown a vertical column for each day of the week. A

series of horizontal lines intercept the vertical lines on the pages 11 forming horizontal columns 13 for a purpose which will presently be explained.

Hingedly mounted or folded on one of the 55 marginal edges of the cover herein shown on the left hand edge and formed integrally therewith is a flap 14. The crease between the flap and the leaf 10 is so formed that the flap normally folds inwardly. This flap it 60 will be noted is provided with a series of horizontal lines on its upper surface when folded, which lines register with the horizontal lines on the leaves or pages 11. The horizontal columns 13 provided by these lines 65 65 provide spaces for designating the subjects comprising the curriculum, such as, "Arithmetic". The upper space contains the word "Subjects" to indicate the various subjects appearing thereunder. The under surface 70 of the flap is also similarly ruled horizontally which ruling registers with the ruling on the pages 11 as will be noted from Figure 2. These spaces are left blank in the drawings and it will be understood that other additional subjects may be inserted therein as desired.

The furthest vertical column 12 to the left which is not designated may be used for inserting any remarks or data desired pertaining to the various subjects and is especially adapted for confidential data as the column can be concealed from view by the flap, which is substantially the width of the said column.

The flap, being formed of material relatively stiffer and therefore heavier than the pages 11 of the book, tends when folded to keep the pages down thereby acting as a weight to prevent the pages from turning accidentally. Furthermore owing to its stiffness, it is readily insertable between the pages 11 and thus affords a ready book mark as will be understood.

The book is used as follows: In the vertical column opposite the particular subject is 95 placed a sample of the branch of that subject taught on any particular day appearing at the top of the column. For example, in the "Monday" column, opposite the subject "Arithmetic" I have shown a sample of an 100

example in fractions, addition being the particular branch of fractions being taught on that particular day. In the "Wednesday" column, opposite the same subject I have shown a sample of multiplication of fractions, that being the particular branch of the subject being taught on that day. This will readily and visually indicate to a substitute or to the principal that on Monday that particular branch of arithmetic is being taught, and that on Wednesday multiplication of fractions is being taught. The same planning for the other subjects may be followed. By reason of this novel arrangement of flap and ruled pages, the principal and substitute can see at a glance the particular subjects taught on a certain day of the week thereby avoiding confusion.

The printing on the cover of the book and flap portion eliminates printing on the individual sheets, thereby saving considerable expense and permitting the entire page to be used for placing working data.

While my invention is illustrated and described as a daily plan book for teachers, it will be understood that my improved book could be adapted for use as a book for keeping the time of employees. This could be accomplished by placing the names of the employees on the flap and by placing the time of such employees in the daily vertical columns. Other uses for my improved book will readily suggest themselves.

It will also be understood that various changes in details might be made therein without departing from the principle of the invention, and I desire therefore to be limited only by the state of the prior art and the appended claims.

40 I claim:

1. A planning book comprising a cover, pages secured therein and having their upper edge extending below the upper edge of the cover, said pages being provided with spaced vertical lines to form a plurality of columns, said cover being provided with written indicia above said columns and a vacant column at the outer edge of each page and being provided with intercepting horizontal lines to form a plurality of subject columns, and a flap formed integrally with one edge of said cover, and adapted to fold inwardly, said flap being provided with a plurality of horizontal lines on the surface which is uppermost when the flap is folded inwardly adapted to register with the horizontal lines of said pages forming columns for the subjects, said flap being provided with indicia between said horizontal lines and said flap being adapted to overlie the said vacant vertical column to conceal any data thereon and to serve as a book mark when folded inwardly.

2. A planning book comprising a cover, pages secured within said cover and being

provided with a plurality of marked off spaces in horizontal and vertical alinement, and a flap attached to the cover and adapted to fold inwardly thereon, said flap having a plurality of marked off spaces on the surface which is uppermost when the flap is folded inwardly, said spaces on the flap being in horizontal alinement with the spaces on the pages.

In testimony whereof I hereunto affix my signature.

EUGENE F. IRWIN.
